CLAIM

The ornamental design for an organizer kit, as shown and described.

DESCRIPTION

FIG. 1 is a perspective view of an organizer kit showing my new design;

FIG. 2 is a front elevational view with the rear view being a mirror image thereof;

FIG. 3 is a right side elevational view thereof;

FIG. 4 is a left side elevational view thereof; and,

FIG. 5 is a top plan view with the bottom view being a mirror image thereof.

The broken lines shown in the drawings represent unclaimed portions of the organizer kit and form no part of the claimed design.
